CLAIM

The ornamental design for a baking sheet, as shown and described.

DESCRIPTION

FIG. 1 is a top perspective view of a baking sheet; FIG. 2 is a bottom perspective view of the baking sheet of FIG. 1;

FIG. 3 is a top plan view of the baking sheet of FIG. 1;

FIG. 4 is a bottom plan view of the baking sheet of FIG. 1;

FIG. 5 is a left side elevational view of the baking sheet of FIG. 1;

FIG. 6 is a right side elevational view of the baking sheet of FIG. 1;

FIG. 7 is a front elevational view of the baking sheet of FIG. 1;

FIG. 8 is a rear elevational view of the baking sheet of FIG. 1; and,

FIG. 9 is a sectional view of the baking sheet taken along section lines 9—9 of FIG. 2.
